UNITED STATES PATENT OFFICE

2,129,214

DRIER

Albert S. J. Hopkins, Amherstdale, W. Va.

Application December 17, 1935, Serial No. 54,921

3 Claims. (Cl. 34—38)

My invention relates generally to driers, and particularly to a de-watering device for removing extraneous moisture and fine particles of coal from washed coal of different sizes, and an important object of the invention is to provide an economical and efficient arrangement of this character, for application to shaker screens.

Another important object of the invention is to provide a device of the character indicated where-
10 in during the progress of the drying, the moisture on the coal is partly removed through the subjec-
tion of different facets of the coal to high pressure
air jets or nozzles, and wherein the water which
is driven off and the fine particles of coal are
15 delivered to a recovery system or permitted to go
to waste as desired.

Other important objects of my invention will be apparent from a reading of the following de-
scription in connection with the drawings, where-
20 in for purposes of illustration I have shown a
preferred embodiment of my invention.

In the drawings:—

Figure 1 is a general horizontal sectional view
25 through a portion of the embodiment showing the
heated blower pipe and the travel of the heated
air under pressure to the nozzles under which the
coal lies.

Figure 2 is a longitudinal vertical sectional view
30 taken through another portion of the ap-
paratus showing the shaking screen and there-
under the water and fine coal stationary hopper
leading to the water and fine coal recovery and
showing the dried coal conveyor.

Figure 3 is a transverse vertical sectional view
35 taken through Figure 2.

Figure 4 is a perspective view of the water
and fine coal receiving hopper.

Referring in detail to the drawings, the nu-
meral 5 generally designates the wire screen to
40 which the wet coal is fed by some suitable means
and which is declined as indicated so that gravity
may aid the travel of the coal along the screen
5 to the trough 6 of the dry coal conveyor (not
shown). The screen 5 has sides 1 and 8 which
45 hold the coal in place on the screen and above
the sides and overlying and across the screen
are the air headers 9 which have depending lon-
gitudinally elongated nozzles 10 which open at a
point close to the coal and have adjustable open-
50 ings to enable adjusting the blast against the
coal. The headers 9 have one end connected to
the header pipe 11 which is connected to a suit-
able supply of air under pressure properly heat-
ed or unheated. The effect of the play of the
55 nozzles on the coal on the screen 5 is to blow off

the extraneous moisture on the coal and to pass
through the screen and into the water and fine
coal hopper 12 the removed water and the fine
moisture on the coal is removed mostly by physical
force breaking down the film of water and this
5 water is driven through the woven wire screen 5.
As the coal passes along the screen it comes into
contact with additional nozzles and the coal pre-
sents new faces or facets for contact by the air,
10 successively, so that by the time the coal has
reached the dried coal conveyor, the same is ac-
tually dry. Of course, some of the moisture will
in the procedure be absorbed by evaporation.

The removed water and fine particles of coal
15 are caught in the stationary hopper 12 from
which they may be sluiced to a sludge recovery
system or permitted to go to waste, according to
desire.

It is to be observed that the hopper 12 is of
20 generally rectangular form provided with an in-
verted pyramidal lower part which has on its
upper edges sides 13 and 14 which are tapering
and have their narrow ends adjacent the dry coal
conveyor 6, the sides and ends having their upper
25 edges close to the screen 5. The apex of the
pyramidal walls of the stationary hopper open
into the conduit 15 which leads to the sludge
recovery system or the waste.

Of course, the mesh of the screen 5 will be
30 suitable to withhold the size of coal desired and
permit smaller particles of coal to fall there-
through into the hopper 12.

A suitable blower (not shown) will be connect-
ed to the blower pipe 11 to blow suitably heated
35 or unheated air into the blower pipe and into
the headers 9, and through the nozzles 10 onto
the coal on the screen 5.

Although I have shown and described herein a
40 preferred embodiment of my invention, it is to
be definitely understood that I do not desire to
limit the application of the invention thereto,
and any change or changes may be made in the
materials, and in the structure and arrangement
45 of the parts, within the spirit of the invention
and the scope of the subjoined claims.

What is claimed is:—

1. In combination a coal shaker including an
inclined screen on which the wet coal is received
and moves, said screen including side walls, a
50 hopper beneath said screen for receiving mois-
ture and particles falling from the coal on the
screen, a blower manifold running alongside of
said screen, a plurality of transverse headers ex-
tending from said manifold and above and across
55

- said screen, each header being formed longitudinally on its underside with a relatively narrow nozzle for directing air under pressure downwardly through the coal on said screen for physically stripping the coal of moisture and loose particles and depositing the moisture and particles in said hopper as the coal moves from the upper toward the lower end of the screen, said nozzle depending below the upper edge of the side walls 10 and extending substantially the full width of the screen.
2. In combination a coal shaker including a screen on which the wet coal is received, said screen including side walls, a hopper beneath said screen for receiving moisture and particles falling from the coal on the screen, a blower manifold running along a side of said screen, a plurality of transverse headers extending laterally from said manifold and above and across 15 said screen, each header being formed longitudinally on its underside with an elongated nozzle for directing air under pressure downwardly through the coal on said screen for physically stripping the coal of moisture and loose particles and depositing the moisture and particles in said hopper, each of said jets comprising a skirt depending from the edges of correspondingly

shaped openings in the bottom wall of the headers, the longitudinal walls of said skirt being substantially parallel.

3. In combination a coal shaker including an inclined screen on which the wet coal is received and moves, said screen including side walls, a hopper beneath said screen for receiving moisture and particles falling from the coal on the screen, a blower manifold running along a side of said screen, individual transverse headers extending laterally from said manifold and above and across said screen, each header being formed longitudinally on its underside with a longitudinally elongated nozzle extending substantially the full width of the screen for directing air 5 under pressure downwardly through the coal on said screen for physically stripping the coal of moisture and loose particles as the coal moves along the screen from the elevated to the depressed end thereof and depositing the moisture 10 and particles in said hopper, each of said jets comprising a continuous wall depending substantially perpendicular from the edges of a longitudinal opening formed in the bottom wall of the header, and to a point below the upper edges 15 of the side walls of the screen.

ALBERT S. J. HOPKINS.
